UNITED STATES PATENT OFFICE

JOHN JOHNSON AND LUTHER G. WILLIAMS, OF BONNE TERRE, MISSOURI.

RADIATOR FOR MOTOR-VEHICLES.

1,173,805.

Specification of Letters Patent. Patented Feb. 29, 1916.

Application filed March 29, 1915. Serial No. 17,711.

To all whom it may concern:

Be it known that we, JOHN JOHNSON and LUTHER G. WILLIAMS, citizens of the United States of America, residents of Bonne Terre, 5 in the county of St. Francois, State of Missouri, have invented certain new and useful Improvements in Radiators for Motor-Vehicles, of which the following is a full, clear, and exact description, reference being had 10 to the accompanying drawings, forming a part of this specification.

Our invention relates to a radiator for motor vehicles, one of the objects being to produce a radiator having water tubes 15 which are so constructed and arranged that they can be easily and quickly cooled by the action of an air current passing through the radiator.

Another object is to produce a simple radiator structure the elements of which are 20 accessible for the purpose of making repairs, and also for the purpose of removing scale or other matter from the interior of the water conductors.

A further object is to provide an improved means for controlling the circulation 25 of water through the radiator.

Figure I is a front elevation of a radiator embodying the features of our invention. 30 Fig. II is an enlarged fragmentary side elevation, showing the parts near the lower end of the radiator. Fig. III is an enlarged horizontal section taken on the line III—III, Fig. I. Fig. IV is an enlarged vertical section, partly broken away, taken approximately on the line IV—IV, Fig. I. Fig. V is a section taken approximately on the line V—V, Fig. VI. Fig. VI is a vertical section taken approximately through 35 the middle of the radiator.

The radiator we have shown to illustrate the preferred form of our invention comprises an upper compartment A having an inlet opening 1, an upper manifold B arranged immediately below said upper compartment and provided with an inlet port 3 for the admission of water from said compartment, see Fig. VI. The upper compartment A comprises a top wall 4, inclined side walls 5, a front wall 6, and a rear wall 7. The upper manifold B comprises an upper member 8, in the form of an inverted trough, arranged between and secured to the walls of the upper compartment A. The lower half of the manifold B is a trough 55 shaped member 9, flanged outwardly at its upper edge and secured to the manifold member 8. A lower manifold C is connected to the upper manifold B by means of vertical water tubes 12. The manifolds 60 B and C are also connected by vertical channel shaped members 13 arranged at the sides of the radiator, as shown most clearly in Figs III and VI.

14 designates a discharge pipe leading 65 from the lower manifold C.

Partition members 15 divide the upper manifold B into a plurality of compartments, and the lower manifold C is divided by partition members 16.

The water enters the radiator at the inlet port 1 near the upper end of the chamber A, see Fig. VI, circulates through this chamber and then flows through the port 3 to a compartment 17 of the upper manifold 75 B. By arranging the partition members 15 in the upper manifold B, I provide the compartment 17, just referred to, and also provide compartments 18 and 19. These different compartments 17, 18 and 19 have no 80 direct communication with each other, and the water entering the compartment 17 can only escape by flowing downwardly through the vertical tubes which communicate with said compartment 17. Water flowing downwardly from the last mentioned compartment passes through certain tubes 12 and enters a compartment 17' in the lower manifold. It will be noted that the water is 85 free to flow upwardly from the compartment 17' to the compartment 18 of the upper manifold, and then downwardly through certain tubes 12 to the compartment 18' of the lower manifold.

Thereafter the water circulates upwardly through certain water tubes, flows into the compartment 19 of the upper manifold, and then flows downwardly into the compartment 19' of the lower manifold. The discharge pipe 14 leads from the compartment 19'. By dividing the upper 95 and lower manifolds into compartments which have no direct communication with each other and arranging the water tubes as shown in the drawings, all of the water 100

must circulate through all of the different compartments, of the different manifolds before reaching the discharge pipe 14. The water is, therefore, gradually cooled as it passes through the series of water tubes which are subjected to the action of an air current, as is well understood in this art.

20 designates air tubes extending through the upper chamber A and secured to the front and rear walls of said chamber. The object in arranging the air tubes at this point is to permit air to circulate through the upper portion of the radiator, thereby cooling the water to a certain extent before it enters the upper manifold B.

To insure a most effective cooling action, the blade-shaped water tubes 12 are preferably flattened, and the side walls of each tube preferably converge from its very narrow rear edge toward the front of the radiator, as shown most clearly in Fig. III. By flattening the tubes in this manner and arranging them as shown in Fig. III, a very large area of the surface of each tube is exposed to the current of air which circulates between the tubes. The water tubes 12 are preferably arranged in two rows, the tubes of each row being in a plane between the tubes of the other row so that each tube is exposed to the air passing through the radiator.

21 designates a screen arranged in front of the water tubes 12 to prevent dirt, leaves and other matter from passing into or through the radiator at this point. 22 designates a similar screen arranged in front of the air tubes 20. The screen 21 is preferably fastened to the frame 23, the latter being detachably secured to the radiator so that it may be readily removed when it becomes necessary to repair the tubes 12 or to stop leakage by applying solder at the junction of a tube and a manifold.

24' designates drain cocks secured to the lower manifold C to permit the drainage of water from the compartments 17', 18' and 19'.

The lower manifold C is a sectional structure consisting of an upper section 24 in the form of an inverted trough having outturned flanges 25 at its lower edge (Fig. IV). The lower section 26 is a trough shaped member having outturned flanges 27 at its upper edge. These flanges 25 and 27 extend around the trough shaped members and lie close to each other as shown in Fig. IV. 28 designates packing arranged between flanges 25 and 27. The means for securing the manifold sections to each other comprises a pair of bars 30 arranged on opposite sides of the radiator, each of said bars being provided with a longitudinal groove 31 for the reception of flanges 25 and 27. The walls of the grooves 31 are preferably inclined, Fig. IV, and the flanges 25 and 27

are preferably provided with inclined members 32 which engage the walls of said grooves 31. The inclined members 32 are preferably wedge shaped elements soldered or otherwise secured to the flanges 25 and 27. The grooved bars 30 are connected to each other at their ends by means of bolts 35, passing through the ends of said bars, Fig. III, and provided with nuts 36 which may be adjusted to force the bars toward each other. When the bars 30 are securely connected by the bolts 35, the flanges 25 and 27 of the manifold sections are forced toward each other to prevent leakage at the junction of these manifold sections.

Obviously, the lower manifold section may be very easily and quickly removed by merely removing the nuts 36 from the bolts 35 and then releasing the bars 30 from the manifold. This is quite important for the reason that it permits the user to clean all of the long vertical water tubes 12 by merely removing the lower half of the manifold C, and then inserting a suitable cleaning tool into the tubes.

Since all of the tubes are exposed when the lower section of manifold C is removed, the radiator may be cleaned very quickly and thoroughly.

Another advantage is that the sediment which accumulates in the lower portion of the radiator may be easily removed from the detachable lower section of the manifold C.

40 designates lugs secured to the bottom wall of the lower manifold and adapted to be secured to a part of the motor vehicle by bolts 41, shown in Fig. I.

42 designates the usual filling tube secured to the upper end of the radiator to permit the introduction of water into the system.

We claim:

1. A radiator comprising water conductors including a manifold having two sections, and means for uniting said sections, said means including a pair of fastening devices arranged on opposite sides of the manifold and means for connecting said fastening devices to secure them to the manifold.

2. A radiator comprising water conductors including a manifold comprising sections each of which is provided with a pair of outturned flanges, fastening devices arranged on opposite sides of said manifold, said fastening devices being grooved to receive said flanges, and means for connecting said fastening devices to secure said manifold sections to each other.

3. A radiator comprising water conductors including a manifold comprising sections each of which is provided with a pair of outturned flanges, and means for detachably securing said sections to each other, said means including a pair of bars arranged on opposite sides of the manifold and provided with grooves for the recep-

tion of said flanges, and means for connecting said bars.

4. A radiator comprising water conductors including a manifold composed of sections each of which is provided with a pair of outturned flanges, a pair of bars arranged on opposite sides of the manifold and provided with grooves for the reception of said flanges, said bars being adapted to force said manifold sections toward each other, 10 and bolts connecting the ends of said bars.

JOHN JOHNSON.
LUTHER G. WILLIAMS.
